UNITED STATES PATENT OFFICE.

GUSTAVE E. VILLARET, OF LEONIA, NEW JERSEY, ASSIGNOR TO OWEN WALSH M'FG. CO., INC., OF NEW YORK, N. Y., A CORPORATION OF NEW YORK.

DESIGN FOR A PANEL FOR A LIGHTING FIXTURE.

Application filed April 11, 1927. Serial No. 21,540. Term of patent 8½ years.

To all whom it may concern:

Be it known that I, GUSTAVE E. VILLARET, a citizen of the United States, residing at Leonia, Bergen County, New Jersey, have invented a new, original, and ornamental Design for a Panel for a Lighting Fixture, of which the following is a specification, reference being had to the accompanying drawing, forming part thereof.

Figures 1 and 2 are elevational side and end views respectively of a panel for a lighting fixture, showing my new design.

I claim as my invention:

The ornamental design for a panel for a lighting fixture substantially as shown.
